UNITED STATES PATENT OFFICE

2,309,505

ENGINE-DRIVEN PUMP

Lawrence Hathaway, Coventry, England, assignor
to Coventry Climax Engines Limited, Coventry,
Warwickshire, England

Application December 1, 1941, Serial No. 421,215
In Great Britain August 21, 1940

6 Claims. (Cl. 103—23)

Our main object is to provide improved means for the priming of an engine-driven pump, particularly a centrifugal type of pump, and particularly in the case of a pumping unit using an engine of relatively-low power. For a pumping unit having an engine of relatively-high power priming can be effected by an exhaust ejector action, but this is not satisfactory when the engine is of relatively-low power.

The invention consists in the combination with an engine-driven pump, of a reciprocating-type of priming pump which is mounted so as to be bodily movable from an inoperative position to a position in which it can be held by the operator to coact with actuating means, driven by the engine, for priming purposes. Preferably the priming pump is of the diaphragm type operable by an engine-driven cam in the form of an eccentric, being spring-pressed towards the inoperative position so that it has to be held in the operative position during priming.

In the accompanying sheet of drawings—

Figure 1 is a side elevation of a pumping unit provided with priming means according to the invention, though the actual priming pump is omitted;

Figure 2 is an end elevation of the priming means of Figure 1, showing the priming pump;

Figure 3 is a part-sectional side elevation showing parts of Figure 1 to a larger scale;

Figure 4 is a perspective view, to a still larger scale, mainly of the eccentric; and

Figure 5 is a perspective view, to a smaller scale, of the supporting base of the unit.

In the construction illustrated, there is a unit incorporating a small internal-combustion engine 11 of, say, 1 H. P., adapted to have its crankshaft 12 coupled, preferably through a flexible coupling 13, with the shaft 14 of a centrifugal pump 15. The unit is mounted on a base plate 17 which is in turn mounted upon a tubular cradle 18 formed of two longitudinals terminating at their ends with upwardly-raised loops 19. The loops can be gripped when the unit is to be transported and the longitudinals serve as runners if it is to be slid along the ground.

The priming pump, indicated at 22, is conveniently disposed between the engine and the centrifugal pump, the driving cam, in the form of an eccentric 23, being either on the crank-shaft or preferably on the pump shaft as illustrated. In a preferred arrangement, as shown by Figures 2, 3 and 4, the eccentric 23 is encased in an oil-retaining bush 24 which is secured

against axial movement thereon in any convenient way, as by means of circlips 25, the external surface of the bush being adapted to engage the lever arm 26 of the priming pump. The eccentric is keyed on the pump shaft 14 and endwise located between the driven flange 21 of the coupling 13 and a spacer 28, the latter engaging at its other end the adjacent end of a support 29 for a bearing for the pump shaft 14.

The priming pump is preferably a diaphragm-type of pump of a known form, having a flange 31 which is bolted or otherwise secured against a corresponding flange 32 on a hand-lever 33 pivotally-mounted at 34 upon a bracket 35 which is in turn supported from some part of the unit, for example, the base plate thereof or the centrifugal pump itself. In the present instance the lever arm 26 of the priming pump extends through slots 37 provided in the said flanges.

The hand-lever 33 is formed with an out-turned toe 38 working in a slot 39 in the bracket 35. A spring means, here shown as a tension spring 41, is provided to bias the hand-lever and priming pump as a whole to carry the lever arm 26 away from the eccentric, the toe 38 then engaging one end of the slot 39 to provide a stop. An adjustable screw 42 co-operates with the other end of the slot to provide a stop in the other direction, when the hand-lever is pulled to carry the lever arm 26 into contact with the eccentric against the bias of the spring, as is shown in Figure 2.

The priming pump is preferably enclosed by a cowling, as shown at 43, the latter having an opening 44 through which the hand-lever 33 extends. The inlet side of the centrifugal pump is provided at some convenient place (45) with a nipple which is connected by a connection (not shown), including a flexible portion, leading to the inlet side of the priming pump. The outlet side of the latter is connected by a pipe (also not shown) running to waste.

When the centrifugal pump is to be used, the engine is first started up, a main valve 46, controlling the outlet 47 of the centrifugal pump, is closed, and the hand-lever 33 is then pulled to carry the priming pump to the operative position. The hand-lever is held in this position until priming is effected, which will be evidenced by the delivery of water (or whatever material is being pumped) from the outlet pipe of the priming pump. Thereupon the hand-lever 33 is released and the main valve 46 of the centrifugal pump can be opened.

What I claim as my invention and desire to secure by Letters Patent of the United States is:

1. In a device of the character described, a driving shaft, a cam operated by said shaft, a reciprocating type pump, a support movably disposed in proximity to said cam and secured to said pump, a pivoted lever having one end operatively connected to the reciprocating element of said pump and its other end extending toward said cam, and means to move said support to bring the lever into operative engagement with the cam to move the lever about its pivot and operate said pump.

2. In a device of the character described, a driving shaft, a cam operated by said shaft, a reciprocating type pump, a support movably disposed in proximity to said cam and secured to said pump, a pivoted lever having one end operatively connected to the reciprocating element of said pump and its other end extending toward said cam, and means to move said support to bring the lever into operative engagement with the cam to move the lever about its pivot and operate said pump, and means biasing said support and lever to their inoperative positions in which the lever is out of contact with said cam.

3. In a device of the character described, a driving shaft, a cam operatively secured to said shaft, a support movably disposed adjacent said cam, a diaphragm-type pump secured to said support and movable therewith, a movable lever operatively connected at one end to the diaphragm of the pump, and having its other end extending towards the cam, and means to move said support to bring the lever into operative engagement with the cam so that operation of said cam acts through said lever to operate the pump diaphragm.

4. In a device of the character described, a driving shaft, a cam operatively secured to said

shaft, a support movably disposed adjacent said cam, a diaphragm-type pump secured to said support and movable therewith, a movable lever operatively connected at one end to the diaphragm of the pump, and having its other end extending towards the cam, and means to move said support to bring the lever into operative engagement with the cam so that operation of said cam acts through said lever to operate the pump diaphragm, and means biasing said support and lever to their inoperative positions in which the lever is out of contact with the cam.

5. In a priming mechanism for use with a centrifugal pump, a drive shaft, a cam operated by said shaft, a base, a supporting arm pivoted to said base, a reciprocating-type priming pump carried by said supporting arm, a lever operatively connected at one end to the reciprocating element of said priming pump to operate said pump and having its other end extending toward said cam, and means to move the supporting arm about its pivot to bring the lever into operative engagement with the cam to operate the priming pump through the lever.

6. In a priming mechanism for use with a centrifugal pump, a drive shaft, a cam operated by said shaft, a base, a supporting arm pivoted to said base, a reciprocating-type priming pump carried by said supporting arm, a lever operatively connected at one end to the reciprocating element of said priming pump to operate said pump and having its other end extending toward said cam, and means to move the supporting arm about its pivot to bring the lever into operative engagement with the cam to operate the priming pump through the lever, said base having stop means to limit the movement of the supporting arm about its pivot, and means biasing the supporting arm to its inoperative position.

LAWRENCE HATHAWAY.
